PRESSURE FEED FOUNTAIN TOOTHBRUSH

Frederick J. Pepping, McHenry, and Frank Guerra,
Island Lake, Ill.

Application June 24, 1954, Serial No. 438,996

3 Claims. (Cl. 15—138)

The present invention relates to new and useful improvements in fountain toothbrushes embodying means for connecting a replaceable cartridge thereto containing pressurized toothpaste or dentifrice for supplying the same to the bristles of the brush.

An important object of the invention is to provide cartridge puncturing means carried by the toothbrush to open the cartridge as the latter is attached to the toothbrush and further to provide a control valve in the head of the toothbrush for admitting the toothpaste or dentifrice thereto.

Another object of this invention is to provide equalizing means in the cartridge for the pressurized contents thereof to insure complete discharge of the contents of the cartridge to the toothbrush.

A still further object is to provide a device of this character of simple and practical construction, which is efficient and reliable in operation, relatively inexpensive to manufacture and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a group perspective view;

Figure 2 is a longitudinal sectional view;

Figure 3 is an enlarged transverse sectional view taken on the line 3—3 of Figure 2; and

Figure 4 is an enlarged perspective view of the puncturing prong.

Referring now to the drawing in detail, wherein for the purpose of illustration we have disclosed a preferred embodiment of invention, the numeral 5 designates the toothbrush generally and which includes a stem 6 having a hollow head 7 at its front end provided with bristles 8.

The head 7 is formed with a longitudinally extending internally threaded chamber 9 and from which a passage 10 leads rearwardly through the stem.

A valve seat 11 is threaded in the rear portion of chamber 9 with the rear end of which a conical valve 12 is engaged and closed by a coil spring 13 positioned behind the valve. A valve actuating rod 14 is connected at its rear end to the valve 12 and extends forwardly through the chamber 9 and outwardly at the front end of head 7 and is formed at its front end with a manipulating knob 15 to open the valve 12. One or more guides 16 are threaded into the front end of chamber 9 in which the rod 14 is slidable and the guides are constructed to seal the front end of the chamber. A dispensing opening 17 is formed in the head 7 adjacent the bristles 8.

The rear end of the stem 6 is threaded into a connector or coupling 18 which is formed with a sleeve 19 at its rear end to slidably receive a cap 20 threadedly connected to the front end of a replaceable cartridge 21. The connector 18 also includes a central longitudinally extending internally threaded bore 22 in which a neck 23

2

which projects forwardly at the front end of cap 20 is threadedly connected.

A prong 24 is also threaded in the front end of bore 22 and is formed with one or more longitudinally extending grooves 25 at its side portions.

The cartridge 21 is provided with a central pressure equalizing tube 26 which is secured internally of neck 23 by a tubular connector 27 over the rear end of which the tube 26 is telescopically fitted and with the front end 10 of the connector 27 suitably secured and sealed in the neck. The front end of connector 27 is closed by a puncturable seal (not shown) after the cartridge 21 has been filled under pressure with toothpaste or dentifrice. The filling of the cartridge 21 through the connector 27 and tube 26 creates a pocket of compressed air in the front end of the cartridge and at the outside of the tube 26 and which forces the toothpaste or dentifrice outwardly through the tube and connector when the latter has been punctured by the prong 24.

20 The prong 24 is positioned in the path of connecting movement of the cartridge 21 so that as the neck 23 of the cartridge is connected in the bore 22 the prong 24 will enter the connector 27 to puncture the same whereupon the contents of the cartridge will pass through the 25 grooves 25 into the passage 10 of the toothbrush. Discharge of the toothpaste or dentifrice is controlled by the valve 12.

The toothbrush may be enclosed by a threaded cap 28 provided with a pocket clip 29 for carrying the device in 30 the pocket of a person.

From the foregoing, the construction and operation of the device will be readily understood and further explanation is believed to be unnecessary. However, since numerous modifications and changes will readily occur to 35 those skilled in the art, it is not desired to limit the invention to the exact construction shown and described, and accordingly, all suitable modifications and equivalents may be resorted to, falling within the scope of the appended claims.

40 What is claimed as new is as follows:

1. A toothbrush of a fountain-type wherein the tooth paste is under pressure and is controllably dispensed comprising, in combination, a hollow stem having a head at one end with an axial bore therethrough providing a chamber, said head having bristles and at least one discharge orifice leading from said chamber and adapted to deliver toothpaste to the bristles, said stem having a pressurized tooth paste delivery passage and a valve seat at the juncture of the chamber and passage, a spring closed valve operable in said passage and normally engaging said seat and closing the passage and chamber, a rod slidably mounted in the chamber and connected at one end with the valve and having its opposite end extending through and outwardly beyond an end of the chamber 45 where it is accessible and provided with a push button operating member, the inward end portion of said stem being externally screw threaded, an adapter coupling having a screw threaded portion screwed on the screw threaded end of said stem, the opposite end of said coupling having an integral sleeve and the intermediate portion of the coupling having an axial screw-threaded bore therethrough in communication with said passage, a screw-threaded plug screwed into said screw-threaded bore and having small delivery grooves to permit passage of 50 pressurized tooth paste therethrough and into the passage, said plug having a pointed axial puncturing prong, and a self-contained ready-to-operate and readily applicable and removable cartridge containing tooth paste under pressure of an expelling and propellant gas, said cartridge having an end portion fitted into said sleeve and being provided at the end adjacent said sleeve with a punctur- 55 60 65 70 75 80 85 90 95

able diaphragm, whereby when the cartridge is fitted into the sleeve the prong punctures the diaphragm and provides communicative connection between the cartridge, grooved plug, passage and valved chamber in said head.

2. The structure defined in claim 1, and wherein said cartridge is closed at one end and open and internally screw-threaded at the opposite end, said screw-threaded end being separably connected with a cap and said cap having an axial screw-threaded neck, said neck being provided with the aforementioned puncturable diaphragm and being detachably screwed into the cooperating end of said screw-threaded bore.

3. For use in conjunction with a fountain toothbrush which is characterized by a bristle-equipped head having a chamber for reception of tooth-paste, and a stem connected with said head and having a pressurized tooth-paste delivering passage communicating with the chamber by way of a spring seated normally closed valve and means for manually unseating the valve; a combination handle and dispensing cartridge containing a supply of tooth paste under pressure of an expelling and propellant gas, said cartridge having a screw-threaded neck at one end provided with a puncturable diaphragm, an adapter coupling connectible at one end with a cooperating end portion of said stem and removably connected at its op-

posite end to an adjacent cooperating end portion of said cartridge and provided with an internally-screw-threaded axially disposed bore aligned with the stated neck on the one hand and adapted to be aligned at its opposite end with said pressurized delivering passage, and a screw-threaded plug screwed into the discharge end of the axial bore and having a pointed puncturing prong which serves to puncture the stated diaphragm, said plug also having peripheral grooves which function to permit the passage of toothpaste by way of said grooves from the cartridge into the intake end of the passage in the stated stem.
